UNITED STATES PATENT OFFICE.

EDMUND P. KINNE, OF ALLIANCE, OHIO, ASSIGNOR TO AMERICAN STEEL FOUNDRIES,
OF NEW YORK, N. Y., A CORPORATION OF NEW JERSEY.

COUPLING-LOCK.

1,140,166.

Specification of Letters Patent.

Patented May 18, 1915.

Application filed August 26, 1912. Serial No. 716,993.

To all whom it may concern:

Be it known that I, EDMUND P. KINNE, a citizen of the United States, and resident of Alliance, in the county of Stark and State 5 of Ohio, have invented certain new and useful Improvements in Coupler-Locks, of which the following is a specification.

My invention relates to railway car 10 couplers and has particular reference to a novel coupler lock.

Car couplers, like all other devices which are subjected to extreme strains and blows and which must operate without lubrication, wear rapidly in service. This wear in a car 15 coupler is most apparent in the knuckle pivot pin and knuckle lock. This wear tends to permit the knuckle to open to an increasing extent as the wear progresses. It is well understood that after a knuckle reaches a 20 point in its closed position at which the inner face of the knuckle falls outside a certain specified line, such a coupler is condemned as unsafe in view of the possibility of its becoming disconnected from the 25 knuckle of a mating coupler.

One of the objects of my invention is to construct a coupler having a novel lock so arranged that wear shall be automatically taken up and at the same time permit the 30 ready lifting of the lock from its position in front of the knuckle tail as required.

My invention contemplates a design of lock which shall have curved locking faces, the curves being struck from different radii. 35 To disconnect the lock it is rocked on the curved surface of the shorter radius.

Another object secured by my construction is in the provision against creeping. In 40 service coupler knuckles work up and down vertically and the upward movement carries the lock with it. However, as the knuckle drops to its lowest position it frequently takes a new hold on the lock the lock being again raised as the knuckle is elevated. In 45 my construction it will be noted that if the knuckle raises the lock must also raise and this cannot occur for the reason that the lock must be rocked to displace it. Movement of the lock in line with the vertical axis of the 50 coupler is impossible when in normal locked position.

A further object is to provide means on the head and knuckle adapted to coöperate in order to relieve the knuckle pivot pin 55 from pulling strains. These means include

a lug projecting upwardly from the floor of the coupler and coöperating with a groove on the under surface of the knuckle tail. The forward contacting surfaces of lug and groove are struck on a radius concentric 60 with the pivot pin, whereas the rear surfaces are eccentrically disposed with relation to the pivot pin. An eccentric top pulling lug is also provided. Because of this construction the knuckle is constantly held, when 65 locked, in retracted position and all strain is removed from the pivot pin.

My invention will be more readily understood by reference to the accompanying drawings, wherein,

Figure 1 is a sectional plan view of a coupler constructed in accordance with my invention; Fig. 2 is a section on the line 2-2 of Fig. 1, showing the locking member in locked position; Fig. 3 is a similar section showing the lock in lockset position; Fig. 4 is a section on the line 4-4 of Fig. 1, showing the lock in its normal locked position; Fig. 5 is a similar view showing the lock on the lockset; Fig. 6 is a similar section showing 70 the lock in its extreme elevated position and coöperating with the knuckle thrower; Fig. 7 is a similar section showing an abnormal position of the lock, wear having taken 75 place to such an extent that the lock has dropped to its lowest point, the knuckle meanwhile being held in its usual position; Fig. 8 is a perspective view of one side of 80 my novel lock, and Fig. 9 is a similar perspective view taken from the opposite side. 85

Referring more particularly to the drawings, it will be seen that the coupler, which is of the common Janney type, is composed of a shank 10, head 11, knuckle 12, knuckle pivot pin 13, knuckle thrower 14, lock 15, and lock lifting link 16. The coupler head is provided with a hollow interior arranged to accommodate the knuckle tail, the knuckle thrower and locking block. The locking face 17 of the head is curved on a 95 comparatively long radius. The knuckle tail 18 also has its locking face curved as at 19, on a considerably shorter radius and from a center different from that of the curve 17. The locking block 15 is provided 100 with a curved face 20, corresponding to the curved wall 17, and a curved face 21, corresponding to the curve 19 of the knuckle tail. Thus it will be seen that by the arrangement of curves the lock is narrower 105 110

at its lower end than at its upper end and is in effect wedge-shaped. In Fig. 7 the function of the wedge-shaped lock is shown. In that view it is assumed that the parts have become considerably worn and the lock has descended to its lowest position. It will be understood, of course, that this wearing action has been very gradual and has extended over a period of years but that constantly during such action the knuckle has been kept within the proper lines and always been without excessive clearance. An eye 22 on the top of the locking block forms a connection for the lifting link 16. It will be noted by reference to Figs. 4, 6 and 7 that the eye is located considerably to one side of the center of gravity of the lock. Thus the tendency of the link on a lifting action is to rock or rotate the lock over the curved surfaces 19, 21. This releases the lock from the cooperating curved surfaces 17, 20, and permits its being lifted to free the knuckle.

The coupler head is provided on its interior with a vertical rib 23, thus forming a guide between it and the adjoining wall 24 of the head. Within this guide-way a projection 25 of the lock is adapted to seat. This serves to guide the lock in its vertical reciprocation. The forward portion of the lock is held against an abutment 26 of the coupler wall, as shown in Fig. 1. At the rear of the lock and below the projection 25 I provide a notch 27, which serves as a lockset and coöperates with the ledge 28 formed transversely of the head and located at the beginning of the guide formed by the rib 23. In order to seat the locking block on the lockset, the eye 22 is located to the right of the center of gravity of the lock, as viewed in Figs. 2 and 3. Thus, as the lock is lifted its lower right hand end will be tilted inwardly and as it reaches a point opposite the ledge 28, it will be engaged thereby. This action is assured by the fact that the lock at a point forward of the eye contacts the short arm 29 of the knuckle thrower. In order to remove the lock from the lockset, I provide a groove 30 in the knuckle tail, which coöperates with a projection 31 on the lower front face of the lock. This groove, coöperating with the projection, serves to pull the lock off the lockset during the opening movement of the knuckle and the rear of the lock, dropping below the lockset, will remain at that point during both the opening and closing movements of the knuckle. In Fig. 6 I have shown the lock in its extreme elevated position after contacting and actuating the knuckle thrower 14. As shown in dotted lines in Fig. 4, the projection 25 has one wall inclined. However, as the lock is raised and freed from the curved wall 17 of the coupler head, this angular line will

come into coincidence with the rib 23, and be guided thereby in its further elevation.

It will be noted that the curves of the two locking faces of the lock are drawn from different radii and have different centers 70 from which the curves are struck. The result of this is that as soon as the lock begins its upward movement, the curved surface of the longer radii is freed from contact with the wall. This makes the further upward 75 movement easy as it is without binding action.

In order to secure the freedom of the pivot pin from pulling strains and to obviate clearance between knuckle and coupler head in a longitudinal line, I provide on the floor of the coupler a curved, upwardly projecting lug 32. As shown in dotted lines in Fig. 1, the front face of this lug is curved as at 33, on a radius coincident with the pivot 85 pin center. However, the rear wall is curved eccentrically to the front wall, as at 34. This lug 32 coöperates with a groove formed in the bottom surface of the knuckle tail, its front and rear contacting surfaces 90 being curved to correspond with the curvature of the lug. By this means it will be seen that while an even bearing surface is provided at one side of the lug and groove whereby blows on the knuckle are transferred to the head in line with the pivot pin, on the other side the eccentric surfaces tend to pull the knuckle backward as the wedge lock thrusts the tail to the rear. Thus a very tight fit is assured. This could not be accomplished with a non-wedging lock as will be readily understood. The lug and groove just described are on the lower face of the knuckle tail. I have provided an additional eccentric surface on top of the knuckle as best shown in Figs. 1, 2 and 3. A rib 35 is struck up on the knuckle tail and is provided with an eccentrically curved front face. This front face coöperates with a similar eccentric curved surface 36 formed on the coupler head. This acts in conjunction with the lug and groove on the lower surface of the knuckle to maintain the knuckle in retracted position.

The curves of the different locking surfaces herein shown are only typical and may be changed and other constructions modified without departing from the spirit of my invention.

I claim:

1. In a car coupler, the combination of a coupler head having a curved locking face, a knuckle pivoted in said head, a locking block having a portion coöperating with the curved surface of said locking face, and means for rotating said lock, the center of rotation of said lock falling within the plane of the knuckle tail, substantially as described.

2. In a car coupler, the combination of a

- coupler head, having a curved locking face, a knuckle pivoted in said head, said knuckle having a curved lock-engaging face, a locking member having portions coöperating 5 with the curved surfaces on said head and said knuckle, and means for rotating said lock, the center of rotation of said lock falling within the plane of the knuckle tail, substantially as described.
- 10 3. In a car coupler, the combination of a coupler head, having a curved locking face, a knuckle pivoted in said head, said knuckle having a curved lock-engaging face, a locking member having portions coöperating 15 with the curved surfaces on said head and said knuckle, the curves of said head and said knuckle having different radii, and means for rotating said lock, the center of rotation of said lock falling within the plane 20 of the knuckle tail, substantially as described.
4. In a car coupler, the combination of a coupler head having a curved locking face, a knuckle pivoted in said head, said knuckle having a curved lock-engaging face, a wedge-shaped lock, the locking surfaces of 25 said lock being curved to correspond to the surfaces engaged thereby, and means for
- rotating said lock, the center of rotation of said lock falling within the plane of the 30 knuckle tail, substantially as described.
5. In a car coupler, the combination of a coupler head having a curved locking face, a knuckle pivoted in said head, said knuckle having a curved lock-engaging face, a wedge-shaped lock having locking surfaces curved 35 to correspond with the surfaces engaged thereby, and means for lifting said lock from a point removed from its center of gravity, whereby the lock is rocked in the 40 arc of the curves thereof, the center of rotation of said lock falling within the plane of the knuckle tail, substantially as described.
6. In a car coupler, the combination of a coupler head, a knuckle pivoted therein, a 45 wear-compensating locking block, the contacting surfaces of said block, knuckle and head being curved, and means for rocking said lock to disengage the same from locking engagement, the center of rotation of 50 said lock falling within the plane of the knuckle tail, substantially as described.
